US0D1053567S

(12) United States Design Patent (10) Patent No.: US D1,053,567 S
(45) Date of Patent:  Dec. 10, 2024

(54) HAIR BRUSH HANDLE

(71) Applicant: Olivia Garden International Inc.,
Walnut Creek, CA (US)

(72) Inventors: Anne Christiane Maza, Antioch, CA
(US); Pierre Jacques Rennette,
Antioch, CA (US)

(73) Assignee: Olivia Garden International Inc.,
Walnut Creek, CA (US)

() Term: 15 Years

(21) Appl. No.: 29/865,451

(22) Filed: Jul. 26, 2022

(51) LOC (14) Cl. 04-02

(52) U.S. Cl.

USPC D4/138; D4/127

(57) CLAIM

The ornamental design for a hair brush handle as shown and described.

DESCRIPTION

FIG. 1 is a perspective view of a hair brush handle, showing my new design;

FIG. 2 is a top view thereof.

FIG. 3 is a bottom view thereof.

FIG. 4 is a front view thereof.

FIG. 5 is a rear view thereof.

FIG. 6 is a left side view thereof; and,

FIG. 7 is a right side view thereof.

The broken lines in the drawings depict features that form no part of the claimed design.

1 Claim, 6 Drawing Sheets
